UNITED STATES PATENT OFFICE.

HORACE E. SMYTHE, OF OAKMONT, PENNSYLVANIA, ASSIGNOR TO THE S. R. SMYTHE COMPANY, OF PITTSBURG, PENNSYLVANIA, A CORPORATION OF WEST VIRGINIA.

FURNACE-FEEDING APPARATUS.

No. 887,535.

Specification of Letters Patent.

Patented May 12, 1908.

Application filed December 30, 1907. Serial No. 408,488.

To all whom it may concern:

Be it known that I, HORACE E. SMYTHE, a citizen of the United States, residing at Oakmont, in the county of Allegheny and 5 State of Pennsylvania, have invented or discovered new and useful Improvements in Furnace-Feeding Apparatus, of which the following is a specification.

My invention relates to apparatus for feeding loose material into gas-producers, and other types of furnaces, and has for its object to produce a feeding apparatus which shall deliver material into gas-producers or the like in small quantities and uniformly to 15 all parts thereof.

My invention may also include means for maintaining a gas-seal in the hopper during the feeding operation and for agitating the material so that it will be fed with certainty.

20 Other objects will appear hereinafter.

Referring to the drawings accompanying this specification, Figure 1 is a vertical section of a hopper embodying my improvements, the section being taken longitudinally through the axis of the feed drum 18; Fig. 2, a vertical section taken transversely of the feed-drum; Fig. 3, a plan; Fig. 4, a section on the line 4—4 of Fig. 2; Fig. 5, a view of the upper part of Fig. 2 with the feeding drum in a different position; and Fig. 6, a perspective of the guard for the bearing of the agitator rolls.

On the drawings, 1 designates the top plate of a gas-producer or other apparatus into 35 which it is desired to feed loose material. The plate 1 has the opening 2, in which is the lower end of the hopper-casing 3, secured to the plate 1 by means of screws passed through the flange 4 on the casing into the 40 upstanding flange 5 on the said plate.

The casing 3 is made of three vertical sections 6, 7, and 8 secured together by bolts. The top section, which is flared upwardly, has the annular groove 9 at its upper end in 45 which the cover 10 may be sealed gas tight by water or sand in the well known manner.

The lower contracted end of the section 6 registers with the inlet 11 at the top of the section 7. Horizontal rollers 12, of which 50 there may be any desired number, have their ends journaled in the slots 13 in the inner surfaces of the upper ends of the section 7. These slots extend entirely to the top of the section for convenience of inserting and 55 removing the rollers. The upper section 6

covers the open ends of the slots as shown in Fig. 1. The slots are elongated vertically to permit the rollers to have vertical movement. To prevent the coal from entering the slots above the journals of the rollers, I provide guards which have vertical flanges 14 lying close against the inner faces of the section 6, these flanges having their upper ends beveled as shown. The lower ends of the flanges rest on the reduced ends or journals of the rollers and are held from moving inwardly toward the center of the hopper by their engagement with the shoulders 15 formed at the junction of the rollers with their said journals. The flanges 14 carry 70 outwardly extending portions 16 which lie on the said journals within the slots 13. It will be seen that, as the rollers rise and fall, no coal will enter the slots, as the flanges 14 cover them at all times.

The sections 7 and 8 together have a horizontal drum-shaped interior, provided with the said inlet 11 at the top of the section 7 and the outlet 17 at the bottom of the section 8. In the said drum-shaped interior of 80 the hopper is the central horizontal shaft 25, on which the feed-drum 18 is mounted. The drum has a series of pockets 19 parallel with the shaft. These pockets have the blades or arms 20 and 21 extending from the body or 85 center of the drum to or in proximity to the inner wall 22 of the sections 7 and 8. The blades 20 extend into contact with the said wall 22, but the blades 21 have between their outer edges and the wall 22 the rollers 24 on 90 the said wall 22 and the outer edge of the blades with which they are associated. The shaft 25 is provided with the gear 26 meshing with the pinion 27 on the shaft 28 carrying the handle 29, but it will be understood that 95 this shaft may be driven by steam or other power. The shaft 28 is shown mounted on the standard 30.

The rollers 12 are so located that the blades 20 and the rollers 24 will engage, lift and rotate them as the drum 18 rotates. The number of the blades will be such as to always maintain at least one at each side of the opening 17 and between the opening 11 and the opening 17, so that no gas from the producer can escape during the rotation of the drum 18. All the blades may be with or without bearing 23 and rollers 24, or they may be partly with and partly without rollers

Below the drum 18, the section 8 of the hopper-casing 3 is made preferably circular in horizontal section and has therein vertical partitions 31. The spaces between adjacent partitions and between the lateral partitions and the side of the casing are partially closed at their lower edges by the downwardly inclined floors 32 which spring alternately from opposite sides of the casing. These partitions form with the floors and casing wall a series of chutes which conduct the material, dropped from the drum pockets 19, into different portions of the producer. The materials are by these chutes divided into small quantities and uniformly distributed to all parts of the producer.

Coal being supplied to the section 6, the continuous rotation of the drum 18 will cause a regular and practically continuous feed. The rollers 12 will intermittently roll to agitate the coal in the section 6, thereby facilitating the passage of the coal into the pockets of the drum 18. The drum drops regularly small quantities of coal upon the chutes 32, which subdivide the same and distribute it evenly to all parts of the producer.

Although I have described my invention in connection with gas producers, it will be seen that it is applicable to many other structures. The term furnaces in the claims is intended to include gas producers as well as any other furnace to which the claim is applicable.

I claim—

1. The combination of a feeding drum having pockets therein, a hopper above the drum to feed material to the pockets, laterally movable rollers between the hopper and the drum, and means for rotating the rollers and moving them laterally as the drum rotates.

2. The combination of a feeding drum having pockets therein, a hopper above the drum to feed material to the pockets, and rollers between the hopper and the drum, the rollers being arranged to be engaged and agitated by the drum.

3. The combination of a furnace, a casing having an outlet leading into said furnace, a rotatable feed-drum in said casing, blades on said drum arranged to form a gas-seal with

respect to said outlet, and rollers engaged by said blades for feeding material to said drum.

4. The combination of a furnace, a casing having an outlet leading into the furnace, a rotatable feed-drum in the casing, blades carried by said drum, rollers carried by said blades between the casing and the blades to form a gas-seal with respect to said outlet. 55

5. The combination of a furnace, a casing for feeding material into the furnace, and a plurality of chutes in the casing, having different directions of inclination to subdivide the material and distribute the same in the furnace. 60

6. The combination of a furnace, a casing for feeding material into the furnace, vertical partitions at the bottom of the casing, and downwardly inclined chutes associated with the partitions, the chutes being inclined in different directions. 65

7. The combination of a drum-casing, a feed-drum in the casing, a hopper-casing, distinct from the drum-casing and arranged to discharge material into the drum-casing, agitating rollers between the hopper and the drum, said rollers being mounted in open ended slots in one casing, and the open ends of said slots being covered by the other casing. 75

8. The combination of a furnace, a hopper, agitating rollers mounted to have transverse movement in slots in the inner face of the hopper, shields between the slots and the interior of the hopper, and means for giving said rollers movements transverse of their length. 80

9. The combination of a furnace, a hopper, agitating rollers mounted to have movement transverse of their length by means of slots in the interior of the hopper, shields covering said slots and movable with the said rollers, and means for causing the rollers to move transversely of their length. 90

Signed at Pittsburg, Pa., this 24th day of December, 1907.

HORACE E. SMYTHE.
